LIGHT SOCKET HOLDER

Angelo C. Cuva, 1024 Sumac Drive,
Sunnyvale, Calif. 94086

Filed Sept. 29, 1969, Ser. No. 19,337

Term of patent 14 years

Int. Cl. D8—08

U.S. Cl. D8—259

FIG. 1 is an exploded perspective view of a light socket holder showing my new design;

FIG. 2 is a bottom plan view of the light bracket portion thereof, the top being plain as indicated in FIG. 3; and

FIG. 3 is an elevational view taken from one side of FIG. 2 the opposite side being a mirror image of the side shown.

I claim:

The ornamental design for a light socket holder, substantially as shown and described.
